UNITED STATES PATENT OFFICE.

JOSEPH B. KELLER, OF SCOTTDALE, PENNSYLVANIA.

AERATOR FOR COKE-OVENs.

1,167,901.

Specification of Letters Patent.

Patented Jan. 11, 1916.

Application filed June 20, 1914. Serial No. 846,338.

To all whom it may concern:

Be it known that I, JOSEPH B. KELLER, a citizen of the United States, residing at Scottdale, in the county of Westmoreland 5 and State of Pennsylvania, have invented a new and useful Aerator for Coke-Ovens, of which the following is a specification.

My invention relates to coking coal and more particularly relates to the regulation 10 and control of the air supplied to the coke ovens in the coal coking process.

Heretofore it has been the practice, especially with bee hive ovens, to provide an opening in each oven doorway for the admission of the air necessary in carrying out the coking operations and in so doing little or no account is taken of changes in the direction and velocity of the prevailing winds, or attempts made to regulate the 20 quantity of air supplied to the coke ovens. Such practice results in much more air being supplied than is necessary at times, and an insufficient supply at other times.

One object of my invention, which is applicable for use with ovens of both the bee 25 hive and rectangular type, is to provide an improved apparatus having novel means whereby the amount of air introduced into the oven in coking a charge of coal is determined, regulated and controlled, to the 30 end that the quantity of coke is increased and the quality improved in a given quantity and grade of coal charged into the oven.

Another object of my invention is to provide apparatus whereby the volume and direction of flow of the air introduced into the coke oven in the coking operation is determined and controlled.

A further object of my invention is to 40 provide improved means whereby an inadequate supply of air and consequent retardation of the coking process is prevented, the direction of flow of the air into different parts of an oven is controlled and a more 45 uniform quality of coke is obtained.

A still further object of my invention is to provide novel means whereby the supply of air introduced into the coke oven while coking a charge of coal is regulated, and 50 cutting (*i. e.* the complete combustion of coke to ash) at or in the vicinity of the door is prevented and overcome.

Still further objects of my invention will become apparent hereinafter as the inven-

tion is more fully described in the specification and particularly pointed out in the appended claims. 55

Referring now to the drawings forming part of this specification in which the apparatus is shown applied to a coke oven of the bee hive type, Figure 1 is a sectional side elevation of an oven showing an aerator constructed and arranged and applied for use in the doorway of the oven in accordance with my invention. Fig. 2 is a front elevation showing the doorway of the oven and the aerator in position as applied for use thereon. Fig. 3 is an inverted plan on an enlarged scale of the aerator showing the sliding gates, by which the size of the air 60 inlets to the aerator is varied and the volume of air entering the oven through the aerator is regulated and controlled. Fig. 4 is a side elevation of the aerator on a larger 65 scale. 70

In the accompanying drawings, the numeral 2 designates the interior of the coke oven which is provided with a doorway or opening 3. As shown, the oven 2 has a charge therein and the doorway is "bricked up" with a wall 4 to close the door opening 3 as is done ordinarily in the process of coking coal in bee hive ovens. Heretofore it has been the practice to terminate the temporary wall 4 short of the top of the doorway so as to provide the necessary air opening 75 therein. 80

In applying my improved apparatus to the oven, the aerator 5 is positioned within the opening 3 and the opening or doorway 90 is closed by means of the temporary wall 4 or by a permanent mechanical door if such be preferred, so that all of the air entering the oven 2 after the aerator is placed in position, must pass into the oven through 95 the aerator. 100

As will be seen from the drawings, the aerator 5 is an L shaped hollow box which has a horizontally extending leg 6 of rectangular cross section, opening into the interior of the oven 2, and a vertical leg 7 of similar cross section extending downwardly and opening at its bottom end into the atmosphere. The interior of the rectangular box forming the aerator is provided with a series of substantial partitions 8 which divide the legs of the aerator transversely into a series of separate compartments 9, 10, 11, 105

12, 13 each having its own inlet and an outlet which leads to the interior of the oven. Preferably the interior of the aerator or of the compartments of the aerator is lined 5 with a refractory material 14 which may be asbestos boards or may be refractory material applied to the surfaces while plastic and then dried or baked in place. The vertical leg 7 of the aerator adjacent to its lower 10 open end is provided with a series of horizontally sliding shutter plates or gates 15, 16, 17, 18 and 19 which extend in the compartments of the aerator to regulate the size of the openings through which the air passes 15 into the separate compartments of the aerator. An opening 20 is provided in the front face of the aerator to form a peep hole for inspecting the interior of the oven from time to time and this hole or opening is normally 20 closed by means of the slide 21.

Instead of dividing the aerator into separate compartments by the partitions and providing each with a sliding gate, the aerator may have but a single compartment 25 with a single gate for regulating the size of the air opening in the bottom of the vertical leg of the aerator or the aerator may be divided into separate compartments all served by a single gate or shutter. The 30 aerator is provided on its front face with a series of openings 22 through which the extension tube 23 of a water gage 24 is introduced for the purpose of measuring the draft or pressure of the air passing 35 through the compartments of the aerator into the oven, and the velocity of the air passing into the aerator may be conveniently determined by holding an anemometer 25 at the entrance end of the several compartments in the vertical leg of the aerator, in the manner shown in Fig. 3.

In the operation of ovens equipped with my improved apparatus the coal is burned or coked within the oven 2 in the usual manner and the doorway 3 is closed either with the usual temporary wall 4, or mechanical door, the aerator 5 being placed in position in the doorway and when used in conjunction with the temporary wall, the space between the walls of the doorway and walls of the horizontal leg 6 of the aerator being filled with brick and made air tight by coating with slurry or clay wash. When used in conjunction with a mechanical door 55 the aerator is placed in position as a part of the door simultaneously with the placing of the door in position, or it may be placed in position in the door after the door is in place in the oven if so desired. When the 60 aerator is used in conjunction with a mechanical door no filling in with bricks between the wall of the aerator and the wall of the oven doorway is necessary. The water gage 24 and the anemometer 25 are frequently employed to indicate the pressure 35

and the velocity of air entering each of the several compartments 9, 10, 11, etc., of the aerator.

It has been found by means of a large number of experiments that three and one half cubic feet of air should be introduced into the oven to each cubic foot of gas evolved, and that this ratio of air to gas should be maintained during the coking process in order to obtain the fullest deposition of carbon on and throughout the interstices of the mass of coke from the heavy hydro-carbon evolved in the coking process, and that the air supply should be uniformly distributed within the oven to facilitate uniform coking of the charge. It has also been satisfactorily demonstrated that the gases evolved in the process of coking coal require approximately six cubic feet of air for each cubic foot of gas to promote the complete combustion of the gas, and that only one-half of this amount of air is utilized in maintaining the oven at coking temperature.

The area of the several compartments in the aerator being known, it is readily determined how much air is required at different times in each of the several compartments and experience soon teaches the burner or operator what adjustments are necessary in the sliding gates 15, 16, etc., to supply the most desirable quantity of air under changing atmospheric conditions and changes in the direction of the wind with regard to the front or doorway side of the oven, while the water gage and anemometer enable the pressure and velocity of the currents of air into the oven at any time to be readily checked.

The advantages of my invention will be apparent to those skilled in the art. The apparatus is simple and being strong and durable will last for an indefinite time without requiring expensive repairs.

By the use of my improved apparatus, the flow of air into each oven is regulated and the distribution of the air is controlled, and the yield of coke from the ovens is materially increased in quantity and improved in quality.

Modifications in the construction and arrangement of the parts forming my improved apparatus may be made without departing from my invention as defined in the claims. The apparatus is applicable to rectangular ovens and other changes may be made.

I claim:

1. In a coke oven, the combination with the oven doorway of an aerator positioned in said doorway and comprising a hollow box, L-shaped in cross section and having a horizontal leg and vertical leg, a partition separating the aerator into compartments, outlets on the horizontal leg opening into the coke oven, inlets on the vertical leg opening

on the exterior of the oven and sliding plates forming shutters or gates to regulate the flow of air through the aerator compartments.

5. 2. In a coke oven, the combination with the oven doorway of an aerator positioned in said doorway and comprising a hollow box, L-shaped in cross section and having a horizontal leg and vertical leg, partitions 10 separating the aerator into a series of compartments, an outlet on the horizontal leg opening from each compartment into the coke oven, an inlet on the lower end of the vertical leg opening from each compartment 15 on the exterior of the aerator, and means in each compartment for regulating the flow of air therethrough.
3. In a coke oven, the combination with the oven doorway and comprising an L- 20 shaped hollow box having a horizontal leg and a vertical leg, one end of said horizontal leg forming an outlet leading into the coke oven and one end of said vertical leg form-

ing an inlet opening on the exterior of the oven, a partition in said box separating the 25 aerator into compartments and sliding plates or shutters in the compartments to vary the flow of air through said compartments.

4. In a coke oven, the combination with the oven doorway and comprising an L- 30 shaped hollow box having a horizontal leg and a vertical leg, one end of said horizontal leg forming an outlet leading into the coke oven and one end of said vertical leg forming 35 an inlet opening on the exterior of the oven, a plurality of partitions in said box separating the aerator into compartments, and means in said compartments to regulate the flow of air through the compartments.

40 In testimony whereof, I have hereunto set my hand.

JOSEPH B. KELLER.
